UNITED STATES PATENT OFFICE.

JOHN T. JOYCE, OF PLAINVILLE, MASSACHUSETTS.

ORNAMENTAL CHAIN.

SPECIFICATION forming part of Letters Patent No. 290,643, dated December 18, 1883.

Application filed September 21, 1883. (No model.)

To all whom it may concern:

Be it known that I, JOHN T. JOYCE, of Plainville, in the county of Norfolk and State of Massachusetts, have invented an Improvement 5 in Ornamental Chains, of which the following is a specification.

My invention relates to an improvement in ornamental chains adapted for the manufacture of bracelets; and it consists in the improved construction and arrangement of the links, as hereinafter fully set forth; and the object of my invention is to produce a chain of great comparative flexibility having a desirably finished edge.

15 Figure 1 is a face elevation of the chain. Fig. 2 is an edge view of the same. Fig. 3 is an enlarged central section taken in the line $x-x$ of Fig. 1. Fig. 4 is an enlarged section taken in the line $z-z$ of Fig. 2. Fig. 5 is a plan view of 20 the inner side of the two opposite edge-pieces enlarged. Fig. 6 is a central section of the same.

In the accompanying drawings, A A' are the 25 opposite end pieces of the alternate links, made with one end rounded and the opposite end correspondingly hollowed, in order to fit the rounded end of the adjoining link. The link-piece A is provided with a perforation, b, and an indentation, c, and the opposite link-piece, 30 A', is provided with a perforation, c', and an indentation, b'. The end of the connecting-wire B is first placed in the depression c and soldered therein, and the connecting-wire B' likewise inserted in the depression b' and 35 soldered to the link-piece A'. The stud a may be either pressed up on the inner side of the link-pieces A A', or be attached thereto in any suitable manner, and in forming the chain the studs a a are inserted into the opposite ends of the tube C, while the connecting-wires B B' pass through the tubes D D, of 40 elongated cross-section, and, entering the per-

forations b and c, respectively, are secured therein by soldering or otherwise, thus forming a chain by the continued joining of such 45 links to each other. The link-pieces A A' being provided with rounded and hollowed ends, closely fitting each other, secures a desirably finished edge to the chain, and the chain constructed as described will have a great 50 degree of flexibility.

It is to be understood that my improved chain may be made without the employment of the tubes C, and that the tubes C or D may be of any desirable form of cross-section, and 55 also provided with surface ornamentation.

I claim as my invention—

1. The improved ornamental-chain link, formed of the pieces A A', provided with opposite rounded and hollowed ends, and connected to each other by means of the parallel wires B B', substantially as described.

2. The improved ornamental-chain link, formed of the pieces A A', provided with opposite rounded and hollowed ends, and with 65 the studs a, and connected to each other by means of the parallel wires B B', substantially as described.

3. In an ornamental chain, the combination of the end pieces, A A', provided with the opposite rounded and hollowed ends, with the connecting-wires B B', and the tubular links D, of elongated cross-section, substantially as described.

4. In an ornamental chain, the combination 75 of the end pieces, A A', provided with the opposite rounded and hollowed ends, with the connecting-wires B B', the tubular links D, of elongated cross-section, and the intermediate tube, C, substantially as described.

JOHN T. JOYCE.
